DOUCHE

Charles W. Cheek, East Chattanooga, Tenn.

Application July 30, 1934, Serial No. 737,635

4 Claims. (Cl. 128—241)

This invention relates to vaginal douches and has for its object the provision of an inexpensive device which may be easily connected to a fountain or suspended container to receive liquid therefrom and deliver the liquid to the cavity to be treated. It is also an object to provide an adjustable shield and means for controlling the discharge whereby the liquid may be held in the cavity as long as may be deemed desirable. Other objects will appear incidentally in the course of the following description, and the invention resides in certain novel features which will be particularly defined in the appended claims.

In the accompanying drawings:
15 Figure 1 is a longitudinal section through a douche embodying the invention.

Figure 2 is a transverse section on the line 2—2 of Figure 1.

Figure 3 is a detail section, on a somewhat larger scale, on the line 3—3 of Figure 1.

Figure 4 is a detail section on the line 4—4 of Figure 1.

Figure 5 is a longitudinal section, showing a modification.

25 Figure 6 is an end view of the nozzle shown in Figure 4.

Figure 7 is a detail section showing a thimble fitted over the end of the delivery pipe.

Figure 8 is a detail section showing a further modification.

Figure 9 is a section on the line 9—9 of Figure 8.

The delivery pipe 1 is of hard rubber and may be straight, as in Figure 1, or curved, as in Figure 5. At its forward end, the pipe is externally threaded and a thimble 2 may be engaged thereover to protect the threads while the shield is being drawn over the pipe, the thimble being removed and a nozzle substituted therefor after the shield is in position. In Figure 1, the nozzle is shown as a sleeve 3 having an internal stop rib 4 intermediate its ends and internally threaded at both sides of the rib. At its outer extremity, the bore of the sleeve is somewhat enlarged and is smooth, as shown at 5, to receive a hollow stem 6

45 extending from the head 7, the extreme diameter of the head being approximately equal to the diameter of the end of the sleeve. Outlet openings 8 are provided in the stem adjacent the head and stop lugs or other projections 9 are provided 50 on the exterior of the stem to impinge against the end of the smooth bore 5 and thereby limit the insertion of the stem and maintain the head in spaced relation to the sleeve. Water or medicated liquid, flowing through the pipe, will be 55 diverted by the head 7 and will pass through the

outlets 8 and escape through the space between the sleeve and the head with some force so as to reach the walls of the vagina and treat the entire surface thereof.

In Figures 5 and 6, the nozzle is shown as consisting of a hollow or tubular body 10 threaded into the end of the delivery pipe and having radial vanes 11 secured in its open outer end, by having their ends embedded in the walls of the nozzle or by being fixed to a ring which is fast in the 10 nozzle. The vanes or blades are obliquely disposed so that the issuing liquid will be diverted and will impinge against the walls of the vagina in a whirling spray.

At its rear end, the delivery pipe is formed 15 into an elbow 12 having a finger rest 13 at the bend so that the device may be easily and conveniently grasped for insertion into the vagina. The upper end of the elbow is internally threaded to be engaged with a coupling 14 secured in the 20 end of a tube 15 leading from a rubber fountain or bag (not shown) which may be suspended upon a wall or bed frame or otherwise supported in a position above the patient. It will be understood that the fountain is equipped with a valve 25 or other means whereby the water may be cut off until the douche is in proper position and that when the water is released it will flow by gravity to and through the delivery pipe.

The drain pipe 16 is formed integral with a 30 sleeve 17 and extends downwardly and rearwardly therefrom, the sleeve being mounted slidably on the delivery pipe and eccentric thereto, as shown in Figures 1 and 2. At its front extremity, the sleeve 17 is provided with a bead 18 35 and spaced rearwardly from said bead is a second larger bead 19. The bell-shaped shield 20 is carried by the sleeve between the beads 18 and 19 and its inner surface is properly shaped to fit snugly to the beads and sleeve. The sleeve may 40 be drawn over the front end of the pipe while the thimble 2 is thereon to protect the threads, and the shield is similarly drawn onto the sleeve. While the shield possesses rigidity, it has sufficient resiliency to pass over the bead 18 and spring into 45 place behind it, the bead 19 constituting a stop to arrest the movement of the shield on the sleeve, and, for greater security, the shield may be cemented to the sleeve. When the shield is in place it houses the greater portion of the drain 50 pipe 16, a rubber discharge tube 21 being coupled to the drain pipe adjacent the edge of the shield to carry the drainage to a suitable convenient receptacle.

The rear end of the sleeve 17 is formed with a 55

bead 22 and a soft rubber packing sleeve 23 is fitted over said bead, as clearly shown, the front end of the packing sleeve being cemented to the sliding sleeve, if desired, for further security. It will be noted that the soft rubber tube or sleeve 23 fits closely around the delivery pipe behind the sliding sleeve 17 and effectually seals the rear end of said sleeve so that the liquid draining from the vagina cannot leak past the end of the sleeve but must pass to the drainage discharge pipe 21. At the rear of the packing sleeve 23 a split collar 24 is mounted on the delivery pipe 1, said collar having a small flange 25 around its rear end and a larger beveled flange 26 around its front end, said flange 26 entering the rear end of the packing sleeve. A clamping band 27, having mating lugs 28 at its ends, is disposed around the split collar and a bolt 29 is inserted through said lugs and equipped with a nut 30 so that the collar may be firmly clamped to the pipe and positively prevent rearward movement of the packing sleeve. A similar clamping band 31 is secured around the sleeve 23 adjacent the rear end thereof to insure the desired tight fit upon the main delivery pipe 1 to prevent leaking of the drainage.

To hold the liquid in the vagina for a stated period, a stop is provided on the drainage tube 21. I have illustrated a device consisting of opposed spring jaws 32 arranged at opposite sides of the drainage tube and having oppositely projecting handle members 33. When the handles are free, the tube will be compressed, as shown in Figure 4, so that the liquid can not flow therethrough and will, therefore, remain in the vagina. When the handles are pressed toward each other, the tube will be released and the liquid then may escape.

In the modification shown in Figure 5, the sliding sleeve 34 is of greater diameter than the sleeve 17 shown in Figure 1, to accommodate the curvature of the delivery pipe and also provide a large chamber for the discharging liquid. At its rear end, the wall of the sleeve is thickened, as at 35, and provided with an internal annular groove to receive the bead 36 at the front end of the soft rubber packing sleeve 37. A clamping band 38, like the band 31, is fitted around the sleeve 37 and the before-described collar 24 and clamping band 27 are mounted at the rear of the packing sleeve.

In the form shown in Figures 8 and 9, there is employed the same sliding sleeve 34 that is shown in Figure 5, and the packing sleeve 40 is engaged in the sliding sleeve and around the delivery tube in the same manner as the sleeve 37. In this arrangement, the rear end of the packing sleeve is conical in form and is provided with diametrically opposite longitudinal ribs 41, and the split collar 42 is formed with flared extensions 43 which engage around the conical end of the packing sleeve with the ribs 41 fitting in the splits of the collar. This construction provides additional resistance to any tendency of the drain tube to turn about the delivery tube.

In use, the sliding sleeve is moved toward or from the forward end of the pipe 1 so as to establish the desired effective length of the pipe, and

the clamping bands are then fastened to hold the sleeve, shield and adjacent elements in the set position. The delivery tube is then inserted into the vagina with the front end of the shield entering between the lips or in such close contact therewith as to form a seal. Then by proper manipulation of the controls or cut-offs, the liquid may be permitted to flow into the vagina and be held therein or permitted to drain therefrom. When draining, the liquid will pass through the lower portion of the open front ends of the shield and the discharge tube and will pass to the drainage receptacle.

The instrument is simple and can be easily adjusted to fit the vagina and the form given the rear end of the delivery pipe enables the operator to easily tilt the tube, when applying it, in order to obtain the desired close relation between the mouth of the cavity and the discharge tube.

Having thus described the invention, what I claim is:

1. In a douche, a delivery pipe, a drainage tube having a sleeve at one end slidably mounted on the pipe, a packing sleeve fitting tightly about the rear end of the sleeve of the drainage tube, and means for securing said packing sleeve around the pipe at the rear of the sleeve of the tube for sealing the rear end thereof, and a collar adjustably secured about the pipe rearwardly of the packing sleeve with its forward end overlapped by the packing sleeve to form a tight joint.

2. In a douche, a delivery pipe, a drainage tube slidably mounted on the pipe, a packing sleeve secured to the rear end of the drainage tube, a clamping band around the sleeve at the rear of the tube, a collar on the pipe at the rear of the sleeve and engaging in the rear end of the sleeve, and a clamping band around said collar.

3. In a douche, a delivery pipe, a drainage tube having a sleeve at one end fitting about said pipe and adjustable thereon, a cylindrical packing fitting snugly about said pipe rearwardly of the sleeve and having its forward end portion fitted into the sleeve in interlocked engagement therewith, an abutment adjustably secured about the pipe rearwardly of the packing, and means for binding the packing in a set position upon the pipe with its rear end bearing against the abutment.

4. In a douche, a delivery pipe, a drainage tube having a sleeve at one end fitting about said pipe and adjustable longitudinally and circumferentially thereon, a cylindrical packing of compressible material fitting snugly about the pipe rearwardly of said sleeve with its forward end portion in interlocked engagement with the rear end portion of the sleeve, an annular abutment fitting about said pipe rearwardly of said packing and shiftable along the pipe toward and away from the packing, means to secure the abutment in a set position upon the pipe with one end abutting the packing, and means for binding the packing about the pipe with its rear bearing against the abutment.

CHARLES W. CHEEK.
